Inventor

BENJAMIN CRAWFORD,
By HIS ATTORNEY, Ivan Ohremec

UNITED STATES PATENT OFFICE.

BENJAMIN CRAWFORD, OF AUCKLAND, NEW ZEALAND.

EXHAUST-MUFFLER.

SPECIFICATION forming part of Letters Patent No. 794,926, dated July 18, 1905.

Application filed May 4, 1903. Serial No. 165,565.

To all whom it may concern:

Be it known that I, BENJAMIN CRAWFORD, a subject of the King of Great Britain, residing at Auckland, in the Colony of New Zealand, have invented a new and useful Exhaust-Muffler; and I do hereby declare the following to be a full, clear, and exact description of the same.

This invention relates to means whereby the explosive sound caused by the emission of the exhaust from gas and other explosive engines from the exhaust-pipe into the outer air may be silenced. Such sound is caused by reason of the exploded gas emitting from the mouth of the exhaust-pipe and striking the atmosphere in a compact volume.

The principle upon which the present invention has been based consists in receiving the exploded gas in a chamber that is provided with a number of openings for its egress, the total aggregate area of such openings being equal to the cross-sectional area of the exhaust-pipe. The gas only escapes from these openings after it has been caused to take a spiral passage through the chamber. The effect of this temporary detention of the gas is to provide an elastic cushion, upon which the explosion from the exhaust-pipe will strike, being then divided up so as to pass through the outlet-holes in a number of streams.

In describing the appliances devised reference will be made to the accompanying sheet of drawings, in which—

Figure 1 is a cross-section, and Fig. 2 a central vertical section on line 3 4 of Fig. 1.

In the figures the exhaust-pipe *a* enters the outer end of a chamber *e*, provided with a spirally-shaped plate *f*, extending across its width, the inner end or center of which is

closed, so as to afford a spiral passage to the exploded gases that enter the outer end of the passage from the exhaust-pipe. The sides of the spiral are formed with apertures *g* at intervals therein, the aggregate areas of such apertures being made equal to the cross-sectional area of the exhaust-pipe *a*. In this case the exploded gases discharged in masses will be forced through the spiral, so that a portion of them will be divided off and will pass out through the apertures as they pass round the spiral. The great part of each explosion will, however, be delivered into the center of the spiral and will then be broken up, so as to pass out through the apertures in the sides of the chamber. In this case also a cushion of air or gas will always be within the center of the spiral chamber, so that the force of the explosion will be deadened.

What I claim as my invention, and desire to secure by Letters Patent, is—

An exhaust-muffler comprising a pair of parallel plates and a spirally-arranged wall or plate extending between said plates and forming a continuous spiral passage extending from the outer edge to the center, and an exhaust-pipe connected to the outer end of said channel, said parallel plates having openings leading from the channel to the outside air except at the inner end of the channel whereby a cushion at said inner end is formed, substantially as described.

In testimony whereof I have signed this specification in the presence of two subscribing witnesses, this 26th day of March, 1903.

BENJAMIN CRAWFORD.
